DESIGN FOR A JEWELRY FINDING OR THE LIKE

George B. Nielsen, Staten Island, N. Y.

Application December 23, 1941, Serial No. 104,810

Term of patent 7 years

To all whom it may concern:

Be it known that I, George B. Nielsen, a citizen of Denmark, residing at Staten Island, city of New York, county of Richmond, State of New York, have invented a new, original, and ornamental Design for a Jewelry Finding or the like, of which the following is a specification, reference being had to the accompanying drawing, forming part thereof.

In the drawing:

Fig. 1 is a front elevational view of a jewelry finding showing my new design; and

Fig. 2 is an edge view thereof.

The essential features of my design are shown in full lines on the drawing.

I claim:

The ornamental design for a jewelry finding or the like, substantially as shown and described.

GEORGE B. NIELSEN.
